UNITED STATES PATENT OFFICE.

GEO. W. KENNISON, OF NEWBURYPORT, MASSACHUSETTS.

STOVE.

Specification of Letters Patent No. 8,949, dated May 18, 1852.

To all whom it may concern:

Be it known that I, GEORGE W. KENNISON, of Newburyport, in the county of Essex and State of Massachusetts, have invented a new 5 and useful Improvement in Stoves for Heating Apartments; and I do hereby declare that the same is fully described and represented in the following specification and the accompanying drawings, letters, figures, and 10 references thereof.

Of the said drawings Figure 1 denotes a front elevation of my improved stove. Fig. 2 is a vertical, central, and transverse section of it. Figs. 3 and 4 are horizontal and 15 transverse sections, the former exhibiting the fire place grate, the latter the top of the fire chamber and its register.

In the said drawings B represents an upright fire pot cylinder or chamber having 20 a grate E on its lower end and a register A or air opening and valve in its upper part. Such fire pot is made to stand on legs F, F, F, and within a chamber, drum, or cylinder H, which should be constructed so much 25 larger in diameter than the fire pot as to enable air to freely circulate between the two, and pass over the top surface of the register and down through it. Out of the upper part of the fire pot B, I lead a smoke 30 discharge pipe D, and at the lower part of the drum H, I make an opening for the admission of air and one for removal of ashes from under the grate, or in other words I provide the lower part of the drum with 35 an opening, and closing doors *a*, *a*, (which opening and doors may be large enough to enable a person to remove ashes through the opening) and through one or both of the said doors I make one or more air inlets or 40 openings to which I adapt a closing slide or valve as seen at *b*, *b*.

Just above the top of the fire pot or furnace for combustion of the fuel I arrange a door and opening for the admission of fuel, 45 such being seen at *c*, and for convenience of charging the fire pot with coal or fuel I make the top or cover of such fire pot to turn upon a hinge as seen at *d*.

The object of such a construction of a 50 stove is to enable the fuel of its fire pot or chamber to be principally consumed by a downward draft of hot air thrown upon the upper part of the mass, and a slight draft or current of air made to pass upward 55 through the mass.

In the operation of the stove the air to

supply combustion enters the drum through the air passages or openings at *b*. While a small quantity of it will pass up through the grate and the mass of coal or fuel resting on it, a very large portion of it will ascend through the space between the drum and the fire pot, and pass by and in contact with the heated external surface of the fire pot, which surface, to a greater or less extent, is generally red hot in such a stove. In so passing by such heated surface the air receives a large supply of heat radiated from it, which, as it ascends in the drum it distributes against the inner surface of the 60 top and sides of the same, such distribution of the heat preventing the air of the room from contact with a red hot or charring surface and consequently any injurious effects thereon such as usually results from the 65 contact of a burning or charring surface with air. The air having performed the office of distribution of heat descends through the register A and rushes downward upon the combustible gases arising from the fuel 70 in a state of ignition and supplies such gases with the quantity of oxygen required to consume them and keep the upper part of the fuel on fire, so that it shall not only burn downward but by the upward draft be made 75 to burn from the grate upward also.

I am aware that there is nothing new in the arrangement of a furnace or fire chamber within a drum, so that air caused to pass into the said chamber may be heated by contact with the said furnace and afterward 80 made or suffered to escape into a room. In such case, the air that supplied oxygen to the mass of fuel was all made to pass upward and through the fuel and out of the 85 discharge pipe, a conductor of such external air to the fire chamber being so made as to convey the air directly into and up through the mass of coal, without any of it passing into a chamber surrounding the fire pot. 90 It will therefore be seen that stoves and furnaces for heating, which have air chambers for heating air and supplying it to rooms through orifices or pipes are essentially different contrivances from my invention, for 95 in this latter the supply of air for the consumption of the fuel is all let into the drum and made to perform three offices, that is to say, a portion of it passes up into the fuel; the remainder rises upward by the external 100 sides or surfaces of the fire pot, when it receives heat, and distributes the same against 105

the interior surface of the sides and top of the drum. After doing this and being still in a heated state having parted with but a portion of its heat, it next descends through 5 the register A, and mixes with the gases arising from the fuel, and aids them in their combustion so as to cause the fuel to burn downward.

In a stove constructed on my improved 10 plan a most perfect control of the draft and consumption of the coal is attained, with a distribution of radiated heat that renders the stove very pleasant and agreeable in its effect on the air (of the apartment) that 15 impinges against the external surface of the drum. It is therefore that my invention and what I claim consists in a combination of the following particulars or elements, viz:

1. A close drum or chamber made with 20 one or more air inlets and three closing slides or doors in its lower part, and a fuel opening and door at or near its upper part.
2. A fire pot or chamber of combustion,

placed within the said drum and having a grate in its lower part and a smoke discharge pipe leading out of it at or near its upper part.

3. An air space under the fire pot grate. 4. A space between the external sides of the fire pot and the internal sides of the 30 drum and made to freely communicate with the space under the grate.

5. A space above the fire pot or place for the fuel and made to freely communicate with the space around the fire pot.

6. A fuel supply opening and doors and an air register in the top of the fire pot, the whole being arranged and made to operate together substantially as above described.

In testimony whereof I have hereto set 40 my signature, this fifteenth day of January, A. D. 1852.

G. W. KENNISON.
